DESIGN FOR A CHILD'S PLAY PAD

Ruth S. Claflin, Park Ridge, Ill.

Application March 15, 1947, Serial No. 137,630

Term of patent 14 years

(Cl. D92—2)

To all whom it may concern:

Be it known that I, Ruth S. Claflin, a citizen of the United States, residing at Park Ridge, in the county of Cook and State of Illinois, have invented a new, original, and ornamental Design for a Child's Play Pad, of which the following is a specification, reference being had to the accompanying drawing, forming part thereof.

I claim:

The ornamental design for a child's play pad, as shown,

RUTH S. CLAFLIN.
